UNITED STATES PATENT OFFICE

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WARP STOP MOTION FOR LOOMS

Application filed November 2, 1928. Serial No. 316,834.

This invention relates to improvements in warp stop motions for looms and it is the general object of the invention to provide a weight controlled knock-off and actuating element which is preferably located near the front of the loom so as to have direct engagement with the shipper handle.

The invention relates more particularly to the type of motion set forth in reissue patent to Regan No. 14,829 combined with certain features shown in the Holmes Patent No. 1,360,638. In these patents there is employed a non-circular detector rod which must be rocked about its axis periodically. It is necessary to effect this oscillation with the application of a comparatively small force in order not to subject the drop wires to undue strain and it is accordingly an important object of my invention to provide a yielding actuator for the detector rods which shall act not only to rock the latter but to move an actuator relatively to the knock-off device preferably the shipper handle.

It is a more particular object of my present invention to locate the knock-off and actuating mechanism adjacent the front of the loom while the detecting mechanism is located at the rear of the loom and operative to connect these two mechanisms by a control rod acted on by a single cam and lever to rock the detector rods and also operate the knock-off mechanism.

With these and other objects in view which will appear as the description proceeds, my invention resides in the combination and arrangement of parts hereinafter described and set forth in the claims.

In the accompanying drawings wherein I have set forth a convenient embodiment of my invention,

Fig. 1 is a central transverse section through a loom made according to my present invention,

Fig. 2 is a top plan view taken in the direction of arrow 2, Fig. 1, showing the cam lever and the weighted element associated therewith,

Fig. 3 is an enlarged side elevation of the warp stop motion proper shown in Fig. 1,

Fig. 4 is an end view taken in the direction of arrow 4, Fig. 3, and

Fig. 5 is a detail top plan view of certain parts taken in the direction of arrow 5, Fig. 1.

Referring to Fig. 1, I have shown loom frame 10 having the usual bottom shaft 11 which preferably makes a complete revolution every second pick of the loom. The shipper handle 12 is mounted on the shipper shaft 13 and when in the forward full line position shown in Fig. 1 is effective to cause continued operation of the loom.

A supporting rod 14 located near the rear of the loom has mounted thereon the hub 15 of a head 16 in which are located a plurality of bushings 17 each provided with a depending link 18 secured thereto. Each bushing is operatively related to a non-circular detector rod 19 and all of said rods are required to rock in unison by a connector 20 which joins the links operatively together.

The drop wires D are provided with slots 21 the upper ends of which are restricted as at 22. The drop wires are held raised by the warp but when any warp thread breaks the corresponding drop wire will fall so that the restricted portion 22 of the slot may surround the detector rod and by means of mechanism not shown but well understood prevent rocking of said detector rod. The matter thus far described may be substantially the same as the motions set forth in the aforesaid patents and forms no part of my present invention.

In carrying my present improvements into effect I provide a bracket 30 secured to the loom frame and pivot thereto a lever 31 the rear end of which is provided with a roll 32 to have operative engagement with cam 33. The latter has a cam surface 34 which is effective during a certain period in the operation of the loom to depress the roll 32 and therefore elevate the forward end of the lever 31. The forward end of said lever is forked as at 35 and has extending therethrough a pin 36 on which is mounted a weighted element 37. The latter has a limited angular movement about the pin and normally rests on a screw 38 mounted vertically for adjust-

ment in a bracket 39 secured in the loom frame.

An actuator member or rod 40 has the lower end thereof threaded into the weighted element 37 and has the upper end thereof adapted for engagement with a shoulder 41 formed on the shipper handle. A collar 42 is adjustably secured in proper vertical position on the rod 40 and supports a control rod 43 which extends rearwardly. The actuator rod extends loosely through an elongated slot 44 formed in horizontal arm 45 of a bracket 46 secured to the loomside. Said slot extends backwardly and forwardly so as to permit the rod 40 to move forwardly to the dotted line position shown in Fig. 1. The slot 44 serves to hold the upper end of the rod 40 against improper movement away from the loomside and also help to direct the actuator toward the shoulder 41 at the time of stopping due to warp fault.

The rear end of the rod 43 is pivotally connected as at 47 to the connector 20 so that movement of the rod 43 to the right as viewed in Figs. 1 and 3 will cause a rocking of the detector rods 19 in a counter-clockwise direction.

In operation, the cam 33 will act to give the forward end of the lever 31 periodic upward movements. These movements need not be abrupt but can be gradual so that the weight 37 and the rod 40 may be caused to operate smoothly and efficiently. Under normal conditions when the lever 31 is in the inoperative position shown in Fig. 1 with the forward end down the weighted element 37 will rest on the screw 38 and serve to hold the actuator rod 40 in the relatively rear position or to the left as viewed in Fig. 1 in alignment with shoulder 41. As the forward end of lever 31 moves upwardly toward operative position the weight 37 will tend to remain on its supporting screw 38 and thus change its angular relation with the lever. If the drop wires are all raised so that the detector rods 19 are free to oscillate on their axes there will be no resistance offered to the right hand movement of the controller rod 43 and upward movement of the lever 31 will therefore cause the actuator rod to move to the right or to the dotted line position shown in Fig. 1. When in this position it will be clear that the actuator rod is out of alignment with the shoulder 41 so that continued upward movement of said actuator rod will be ineffective to rock the shipper handle.

As the lever descends to its inoperative position the rod 40 will be moved backwardly or to the left to assume its original position and this motion will be communicated through rod 43 to the links 18 to move the detector rods 19 back to a position where a fallen drop wire can move downwardly into restraining position with respect to the rod.

Should any one of the detector rods be held against oscillation, however, because of a warp fault, the control rod 43 will not be free to move forwardly and as the cam lever 31 moves upwardly the weighted element 37 will move away from the adjustable support 38 and the actuator rod 40 will move upwardly with very little or practically no angular movement relatively to the lever 31. As the actuator rod nears the upper limit of its movement under these conditions it will engage the shoulder 41 and rock the shipper handle to the dotted line position shown in Fig. 1 to stop the loom.

From the foregoing it will be seen that I have provided a warp stop motion wherein the detecting elements are at the rear of the loom and the knocking-off and actuating mechanism is located near the front of the loom and both sets of mechanisms are actuated through a single cam operating in conjunction with a weighted element which may undergo a change in its normal operation of moving the actuator rod out of alignment with the shoulder 41 and cause stopping of the loom when the control rod 43 is prevented from moving forwardly by reason of a warp fault.

Having thus described my invention it will be seen that changes and modifications may be made therein by those skilled in the art without departing from the spirit and scope of the invention and I do not wish to be limited to the details herein disclosed, but what I claim is:

1. In a warp stop motion, a non-circular detector rod to be oscillated about its axis and located at the rear of the loom, control mechanism movable from running to stopping position and located at the front of the loom, a regularly moving lever, a weighted actuator member pivoted to the lever beneath the control mechanism and normally in alignment with the latter, and a control rod operatively connected at its rear end to the detector rod and at its forward end to the actuator member, said weighted actuator member being movable by the lever toward the stopping mechanism and tending to move out of alignment with the stopping mechanism and also tending to cause oscillation of the detector rod, inability of the detector rod to rock on its axis holding the actuator member in alignment with the stopping mechanism to move the latter from running to stopping position as the lever moves upwardly.

2. In a loom, a shipper lever, a knock-off member for said lever, a single actuator supporting said member to give the latter periodic working movements toward the shipper lever, a warp stop motion having a rod to be oscillated, connections between the rod and member, a yielding element controlled by the actuator and acting through the connections to tend to oscillate the rod when the member

has a working stroke, and tending to move the knock-off member away from the shipper lever, the connections acting to direct the member toward the shipper lever when the rod is held against oscillation.

5 3. In a warp stop motion, a non-circular detector rod to be actuated about its axis, control mechanism movable from running to stopping position, a weighted actuator member having a portion normally in alignment with the control mechanism, a movable support for the actuating member to move the latter toward the stopping mechanism, a weighted element operatively connected to the actuator member, and a control rod operatively connected at its rear end to the detector rod in such a way as to cause oscillation of the detector rod when said control rod has a longitudinal movement, said control rod at its forward end being operatively connected to the actuator member, the weighted element when the support for the actuator member moves upwardly tending to oscillate the detector rod by a force communicated through the actuator member and control rod, said detector rod when held against oscillation holding the control rod against longitudinal movement to cause the actuator member to have engagement with the control mechanism 20 to move the latter from running to stopping position.

In testimony whereof I have hereunto affixed my signature.

WALTER H. WAKEFIELD.
